UNITED STATES PATENT OFFICE.

EDWARD CHARLES FREMAUX, OF RAYNE, LOUISIANA.

SWING.

1,241,951.

Specification of Letters Patent.

Patented Oct. 2, 1917.

Application filed March 9, 1917. Serial No. 153,587.

To all whom it may concern:

Be it known that I, EDWARD C. FREMAUX, a citizen of the United States, and a resident of Rayne, in the parish of Acadia and State 5 of Louisiana, have invented a new and Improved Swing, of which the following is a full, clear, and exact description.

My invention has for its object to provide a swing having a chair frame pivoted along 10 its center line to a foot frame, the chair and foot frames being supported by independent means, and the chair frame having slots at its side in which are disposed back supports which are pivoted to the chair frame below 15 the seat, and which permit the seat to be reversed as desired.

Additional objects of the invention will appear in the following specification, in which the preferred form of the invention 20 is disclosed.

In the drawings similar reference characters denote similar parts in all the views, in which—

Figure 1 is a perspective view illustrating 25 my invention;

Fig. 2 is a transverse sectional view of the swing illustrated in Fig. 1; and

Fig. 3 is a fragmentary perspective view illustrating another means by which the 30 chair frame may be supported.

By referring to the drawings, it will be seen that the swing is provided with a foot frame 5 having members 6 extending from front to rear, these members 6 being connected at the front and rear by foot rests 7. The chair frame 8 is constructed with V-shaped frame members 9 at its sides, these V-shaped frame members 9 being connected by the seat 10. To the outer members 6 of the foot frame 5 there are secured the ends of a rod 11, the V-shaped frames 9 adjacent the angles formed by their members being pivoted to this rod 11, this means being provided for connecting the chair 45 frame 8 with the foot frame 5.

To the chair frame 8 there are secured anchor members 12, to which are fastened the parts 13 of the support for the chair frame, these parts 13 being connected at 50 14, and being disposed when the chair is at rest on a line which, if extended, would pass substantially at equal distances from the upper portions of the V-shaped frames 9 in the direction of the rod 11. The support 55 13^a which extends upwardly from the point 14, where its parts 13 are united, may be

secured to a supporting frame 15, such as is shown in the drawings, but it will be understood that any desired type of supporting frame may be employed. The foot 60 frame 5 is connected with the supporting frame 15 by means of rods 16, the lower ends of which are articulated to the outer members 6 of the foot frame at 17, the upper ends being articulated to the supporting 65 frame 15 at 18.

In the seat 10 there are slots 19 in which are disposed back supports 20 which carry the backs 21. The back supports 20 are articulated to the rod 11. It will be understood that with this construction, the backs 21 of the chairs may be reversed, and when desired one of the backs 21 may be disposed in one direction and the other back 21 may be disposed in the opposite direction, as 75 illustrated by the full lines in Fig. 1 of the drawings.

It will be seen by referring to Fig. 3 of the drawings, that instead of the supports 13 and 13^a which are shown, bars or links 80 22^a may be secured to the V-shaped members of the frame.

It will be understood that if desired the back 21 may be made in one piece and that the arm rest 22 may be omitted. 85

Having thus described my invention, I claim as new and desire to secure by Letters Patent:

1. In a swing, a foot frame, a V-shaped chair frame, a chair seat for the chair frame, 90 there being slots in the chair frame adjacent the seat, a back for the seat having supports disposed in the slots, and pivotal means connecting the foot frame with the back supports and the chair frame adjacent 95 the angle formed by the V of the chair frame.

2. In a swing, a foot frame, a chair frame pivoted to the foot frame, a chair seat for the chair frame, there being slots in the chair 100 frame adjacent the seat, a back for the seat having supports disposed in the slots and pivoted to the chair frame therebelow.

3. In a swing, a foot frame, a chair frame having a seat, pivoted to the foot frame below a line substantially parallel with and equal distances from the front and back of the seat when the swing is at rest, independent means for supporting the foot frame and the seat frame, there being slots in horizontal portions of the chair frame, and a chair back with supports disposed in the 105 110

slots and pivoted at the pivotal connection of the foot frame and the chair frame.

4. In a swing, a foot frame, a V-shaped chair frame, a chair seat for the chair frame, there being slots in the chair frame adjacent the seat, a back for the seat having supports disposed in the slots, pivotal means connecting the foot frame with the back supports and the chair frame adjacent the angle formed by the V of the chair frame, a rod pivoted to the foot frame and adapted to be pivoted to a support, and supporting means secured to the chair frame, extending upwardly on a line which if extended 10 would pass through the pivotal means, and at substantially equal distances from the upper portions of the V-shaped frame.

5. In a swing, a foot frame, a chair frame having a seat pivoted at its bottom to the foot frame, and a back for the seat pivoted 20 to the foot frame and adapted to pass from the front to the back of the seat.

6. In a swing, a foot frame, a chair frame having a seat pivoted at its bottom to the foot frame, a back for the seat pivoted to 25 the foot frame and adapted to pass from the front to the back of the seat, means for supporting the chair frame, and means for supporting the foot frame.

EDWARD CHARLES FREMAUX.
